US00D906519S

(12) **United States Design Patent** (10) Patent No.: **US D906,519 S**
 Smith et al. (45) Date of Patent: **** Dec. 29, 2020**

(54) **CRANIOSYNOSTOSIS BONE
MANIPULATION DEVICE**

(71) Applicant: **DePuy Synthes Products, Inc.**,
Raynham, MA (US)

(72) Inventors: **Kory Smith**, West Chester, PA (US);
Jeffrey Darrow, West Chester, PA (US); **Steven Krevitski**, Havertown, PA (US)

(73) Assignee: **DEPUY SYNTES PRODUCTS, INC.**, Raynham, MA (US)

(**) Term: **15 Years**

(21) Appl. No.: **29/667,567**

(22) Filed: **Oct. 23, 2018**

(51) LOC (12) Cl. **24-02**

(52) U.S. Cl.

(57) **CLAIM**

The ornamental design for a craniosynostosis bone manipulation device, as shown and described.

DESCRIPTION

FIG. 1 is a front perspective view of a craniosynostosis bone manipulation device in accordance with the present invention showing the new design;

FIG. 2 is a top view thereof;

FIG. 3 is a right-side view thereof;

FIG. 4 is a bottom view thereof;

FIG. 5 is a left-side view thereof;

FIG. 6 is a front view thereof; and,

FIG. 7 is a rear view thereof.

1 Claim, 4 Drawing Sheets
